AEROBIC SEWAGE TREATMENT TANK

Patrick J. Murray, Exton, and John Robert Barry,
Downingtown, Pa., assignors to Nayadic Sciences, Inc.,
Eagle, Uwchland, Pa.

Filed Apr. 12, 1972, Ser. No. 243,537

Term of patent 14 years

Int. Cl. D23—01

U.S. Cl. D23—2

Fig. 1.

Fig. 2.

Fig. 4.

Fig. 3.

FIG. 1 is a side elevation of an aerobic sewage treatment tank embodying our new design, a portion being broken away for convenience of illustration.

FIG. 2 is a plan view thereof.

FIG. 3 is a bottom view thereof.

FIG. 4 is a perspective view thereof.

We claim:

The ornamental design for an aerobic sewage treatment tank, as shown.
